UNITED STATES PATENT OFFICE.

LEO LAUKKI AND JOHN RIIKONEN, OF CHICAGO, ILLINOIS.

LABEL-AFFIXING MACHINE.

1,178,163.

Specification of Letters Patent.

Patented Apr. 4, 1916.

Application filed April 26, 1915. Serial No. 23,803.

To all whom it may concern:

Be it known that we, LEO LAUKKI and JOHN RIIKONEN, citizens of the United States, residing at the city of Chicago, in the county of Cook and State of Illinois, have invented certain new and useful Improvements in Label-Affixing Machines, of which the following is a specification.

This invention relates to improvements in a machine to be used for affixing labels to packages containing, or to contain articles of various kinds, and while it is more particularly intended for use in affixing labels to packages rectangular in shape, such as, the boxes for matches, yet it is applicable for applying labels to packages of different shapes and sizes for holding articles or material of almost any kind, including bottles for beer, medicines and other liquids, and it consists in certain peculiarities of the construction, novel arrangement and operation of the various parts thereof, as will be hereinafter more fully set forth and specifically claimed.

The principal object of the invention is to provide a label affixing machine of the above named general character, which shall be so constructed as to be operable by means of hand or motor power, simple and inexpensive in construction, strong, durable and efficient in operation.

Another and important object is to provide a label affixing machine that can be operated by a single person, and so that the packages can be supplied from the hopper or supply chute, provided with paste or glue on the surface to receive the labels, the labels placed and adhered thereto, and smoothed or cleaned by a brush in immediate succession, and in a very rapid, satisfactory and efficient manner.

Various other objects, advantages and details of the construction of the invention will be disclosed in the subjoined description and explanation.

Referring to the accompanying drawings, which serve to illustrate an embodiment of the invention:—Figure 1— is a face view in elevation of the machine, showing the parts in position ready for operation. Fig. 2— is a side view. Fig. 3— is a horizontal view, partly in section, taken on line 3, 3, of Fig. 1, looking in the direction indicated by the arrows. Fig. 4— is a vertical view, partly in section, taken on line 4, 4, of Fig. 1, looking in the direction in-

dicated by the arrows. Fig. 5— is a similar view taken on line 5, 5, of Fig. 1 as shown by the arrows. Fig. 6— is a longitudinal sectional view taken on line 6, 6, of Fig. 4, showing a portion of the base, a part of the upright main frame and the means for feeding the packages from the chute or hopper. Fig. 7— is a vertical sectional view taken on line 7, 7, of Fig. 4 looking in the direction indicated by the arrows. Fig. 8— is a bottom plan view of the label holder. Fig. 9— is a fragmental vertical sectional view taken on 9, 9, of Fig. 8 looking in the direction indicated by the arrows. Fig. 10— is a vertical sectional view taken on line 10, 10, of Fig. 1, looking in the direction indicated by the arrows, showing the means for gripping and releasing the shank of the weighted plunger for the label holder. Fig. 11— is a vertical sectional view through the paste or glue pot, taken on line 11, 11, of Fig. 1, looking in the direction indicated by the arrows, and Fig. 12— is a detached perspective view of the agitator or plunger for the paste or glue pot.

Like numerals of reference refer to corresponding parts throughout the different views of the drawings.

The main frame of the machine includes a base 15, which is by preference hollow, and an upright box-like portion 16, which is mounted on the base at one side of the longitudinal middle of the same and forms a support and housing for certain parts of the mechanism as will be presently explained. The base 15, may be provided at each of its corners with a leg 17, to rest on a table or other suitable horizontal support for the machine.

That portion of the base adjacent to the operator, which will be termed the rear portion, is provided on its upper surface rearwardly of said housing, with a pair of 109 guide-bars, 18 and 19, which are spaced apart and extend longitudinally on the base and in parallelism with one another from one end of the base 15, to near the other end thereof, and are used for the guidance of 105 the packages as they are moved therebetween in the operation of being labeled. One of these bars, by preference the bar 18, has secured thereto, on its inner surface, a series of inwardly bowed springs, 20, which 110 have their resilient portions free and overlapping the secured portions thereof as will

be clearly understood by reference to Fig. 3, of the drawings, so as to press the packages 21, which are herein shown as match-boxes, and rectangular in shape, but which may be 5 of any desired shape and capable of holding any kind of material, against the bar or guide, 19, individually or collectively, and in such a manner, as to hold the packages against vertical movement incident to 10 the similar movement of the paste or glue-pot to which they may have a tendency to adhere. The upper portion of the base, 15, is provided near and between one of the 15 ends of the bars, 18, and 19, with a longitudinal slot, 22, for the reception and operation of a depending lug, 23, on the feed-plunger carrier, 24, which lies between the edges of said slot and on the top of the base and has its outer end provided with an 20 upward extension 25, in which a screw-bolt 26 is swiveled at its outer portion, and engages with its inner part the feed-plunger or block, 27, which has lateral flanges 28, loosely engaging the sides of the carrier 24 25 thereof. Thus, it will be understood, that by turning the screw 26 in the proper direction, the plunger or block, 27 may be advanced or retracted on the carrier 24 so as to adjust said plunger for feeding or pushing 30 packages of different sizes from the chute or hopper to and between the guides 18 and 19 as said packages are being labeled.

Vertically mounted on the base across the slot 22 therein, and at the ends of the bars 35 18 and 19 adjacent to said slot, is a chute or hopper, which is designated as a whole by the numeral 29, and by preference, consists of a pair of spaced apart uprights, 30 and 31, channeled in cross section, with their 40 channels facing each other so as to receive and vertically guide the packages. The lower ends of the members 30 and 31 are suitably secured to the base 15 and are provided with openings 32 of sufficient sizes to 45 permit of the operation therein of the plunger 27 and of the exit of the packages as they are pushed from the chute by the said plunger. The upright housing 16 is mounted on the base 15 forwardly of the 50 bar 19 and may be secured at one of its ends to the chute 29 as is clearly shown in Figs. 1, 4, and 5 of the drawings.

Horizontally journaled in the upper portion of the housing or main frame 16 is the 55 driving shaft 33, which has loosely mounted on one end thereof, a wheel 34, provided with a handle 35, to be used for turning the same, when it is desired to operate the machine manually. The outer end of the hub 60 of the wheel 34, is provided with a clutch-face 36 to engage a clutch 37 fixed to one end of a shifting-rod 38, which is extended through a bore or opening in the driving shaft. Connected to the other end of the 65 rod 38 is one end of a strap or bar 39,

which is extended upwardly and then horizontally over and along the top of the housing 16, to which top part, the horizontal portion of the bar 39, is movably secured by means of screws 40, extended through slots 70 41 in said bar and seated in the housing. By this arrangement, it is obvious, that by pushing the bar 39 and rod 38 in the direction of the wheel 34, the clutch 37, will be disengaged from the clutch 26, and thus 75 permit the wheel to run idly, which is often desirable when the machine is driven by motive power, which can be done by applying power by means of a bolt or gearing (not shown) to said wheel. To place the 80 wheel 34, in operable connection, with the driving-shaft, it is only necessary to shift the rod 38 in the opposite direction, which will cause the clutches 36 and 37 to engage each other. The hub of the wheel 34 is provided with an internal circumferential groove 42, to receive a pin 43 on the shaft 33, see Fig. 7, to prevent longitudinal movement of the wheel on said shaft.

The lower portion of the main frame or 90 housing 16, is provided with a rearwardly or inwardly extended enlargement 44, which enlargement is provided with a number of vertical openings 45, usually four in number, for the reception of rods 46—47—48 95 and 49, each of which rods has journaled on its upper end a roller, 50, to contact with eccentrics or cams, mounted on the driving shaft, 33, as will be presently explained. The shafts, 46—48 and 49 rest at their lower 100 ends on spiral springs 51 which springs are located in the lower portion of the openings 45 of the enlargement 44, and rest at their lower ends on the top of the base. The rod 47 is provided in its lower portion with a reduced rod 52 or extension which projects through an opening 53 in the top of the base 15 and is pivotally and movably connected at its lower end by means of a 105 pin 54 to a slotted arm 55, which arm is mounted on the shaft 56, which is transversely journaled on the base 15 at about the middle thereof. Located on the shaft 56 rearwardly of the slotted arm 55 is another 110 arm 57, which also extends at a right angle to the shaft 56 and has pivotally and movably connected thereto one end of a bar 58, the other end of which bar is pivotally connected to the lug of the carrier 24 (see Fig. 115 6 of the drawings).

Surrounding the reduced portion 52 of the rod 47 is a spiral spring 59 which rests at its lower end on the top of the base and at its upper end against the lower part of the rod 47. Mounted on the driving shaft 33, and fixed thereto by means of screws 60 or otherwise are a series of eccentrics 61 or cams, which are so located as to contact and coact with the rollers 50 of the rods 46, to 125 49 inclusive. Secured to the rear surface of 130

the enlargement portion 44 of the housing is a vertical plate 62 which has on its rear surface a number, usually three, of vertically disposed and spaced apart guide-bars 63, 64 and 65 which extend upwardly from the upper surface of the rail or guide 19 to near the upper edge of the enlargement 44 of the housing. Each of the guide bars 63 and 65 has on its inner surface a recess 66, and guide bar 64 has on each of its sides a recess 66 which coincide in length with the recess 66 of the outer guide bars. Mounted on the rear part of an enlargement 67, on the upper portion of the rod 46 is a bracket 68 which has at its upper end a rearward extension 69 provided on its upper surface with a pin 70 and at its lower portion with a rearward extension 71 to engage a hook or forwardly extended arm 72 with which the front upper portion of the glue or paste pot 73 is provided. The guide bars 63—64 and 65 are provided above and below the recess in said bars with flanges 74, which flanges are spaced rearwardly from the plate, 62 on which said bars are mounted. The receptacle 73 has on its front portion at its upper and lower parts, lateral flanges 75, which are adapted to operate between the flanges 74 of the bars 63 and 64, and the plate 62. As is clearly shown in Fig. 1, the flanges 75 on the pot 73 are located at the corners thereof, and are spaced apart so that in inserting the pot 73, the flanges 74 at the upper part of the guide bars may be passed between the upper and lower flanges 75 on the pot, until the latter flanges rest against the plate 62, when it is obvious that the pot will be guided for vertical movement. The receptacle or pot 73 has its upper end open and is provided in its lower end with numerous small perforations 76 for the passage of glue or paste onto the packages 21 to be labeled. Loosely located in the receptacle 73, is an agitator or plunger 77 which is of a shape to correspond with the shape of the receptacle 73, usually rectangular in shape and said plunger has a number of perforations 78 in its bottom as well as a slot 79 for the passage of the glue or paste. Mounted on the plunger 77 is a cross head 80 from which extends upwardly a rod 81 which has in its upper end an internally screw-threaded opening 82 to engage the lower portion of a screw-threaded rod 83, which rod is fixed at its upper portion to the knob 84 used for turning the rod 83 so as to adjust the position of the plunger 77 in the glue pot. Fitted loosely around the upper portion of the rod 81 is a sleeve 85 which is swivelly held in position on the rod 83 by means of a shoulder or enlargement 86 on the upper portion of the screw-threaded part of said rod. Fitted around the upper portion of the sleeve 86 is an arm 87 which has an opening 88 in its front portion to receive the pin 70

on the bracket 68, which arrangement will support the plunger 77 at a distance from the bottom of the pot, 73, which distance can be regulated by turning the knob 84 in the proper direction so as to raise or lower the rod 81 and the plunger 77, which it carries.

Extended downwardly from about the middle of the top of the housing 16 and between and rearwardly of the rods 47 and 48 is an arm 89 which terminates at its lower portion in a U shaped member 90 which is located directly in the rear of the rod 48, which rod has on its upper portion an enlargement 91 to the rear part of which is secured a bracket 92 which has on its upper end a rearward extension 93 provided with an upwardly extended pin 94 to fit in an opening 95 in the gripping arm 96, which arm is provided in its other or rear end with a vertical opening 97 to receive the shank 98 of the weighted plunger for the label holder, which plunger is attached to the lower end of the shank 98 in a suitable manner. The lower part of the bracket 92 is provided with a rearward extension 100 which engages the hook or forwardly projected extension 101, on the front upper portion of the label holder, which is designated as a whole by reference numeral 102 and consists of a substantially rectangular box 95 or casing having each of its ends open and provided in one of its side walls with an opening 103 for the purpose of rendering easy access to the labels. The front wall of the holder 102 is provided at each of its sides with vertically disposed flanges 104 which are arranged in pairs at the top and bottom of the holder so that in inserting the holder between the guide bars 64 and 65 thereof, one pair of the flanges 104 can be passed forwardly through the recess 66 of said guide bars until the flanges 104 strike the plate 62, when it is apparent that said flanges will be free to move vertically between the flanges 74 on the guide bars 64 and 65 of said plate. In the walls of the holder 102 a series of vertical openings or bores 105 are provided each of which bores has its upper portion internally screw-threaded to receive the screw plug 106 used for regulating the tension of the spiral springs 107, one of which springs is located in the upper portion of each of said bores as will be readily understood by reference to Fig. 9 of the drawings. Movable located in the lower portion of each of the bores 105 is a rod 107^a which is provided on its upper end with a head 108 against which the lower ends of the springs 107 will rest. Below the head 108 each of the rods 107^a is provided with a reduced portion 109 to permit of some play or vertical movement of said rods. Located in the walls of the holder 102 at about the middle of each of the openings 105 is a screw 110 which, as shown in Fig. 9, is adapted to 130

be extended into the opening 105 so as to restrict the movement of the rods 107^a in either direction. The inner surface of the walls of the holder 102 is provided at the 5 lower portion of each of the openings 105 with a vertical slot 111 which slots communicate with said openings and extend through the lower end of the holder. The walls of the holder are also provided on their outer surfaces at each of the openings 105 with a vertical slot 112 each of which communicates with the openings 105 and extends through the lower end of the holder. Secured to each of the rods 107^a just below the reduced portion 109, is one end of a 10 spring 113 which springs extend downwardly within the slots 111 and which spring each has its lower or free end inwardly deflected as at 114 (see Figs. 4, 8, 9, and 10 of the drawings,) to engage the lowermost one of the labels contained in the holder. Extending through each of the rods 107^a, near its lower end is a screw 115 which is adapted to operate in the slots 111 and 112 and is used for the purpose of adjusting the 15 springs 113 inwardly or outwardly with respect to the holder as before stated. The heavy or weighted plunger 99 is located in the holder 102 for the purpose of striking the group of labels 116 which are placed in the holder 102 one on the other in which position they are retained by the deflected portions 114 of the springs 113 until released from said holder one at a time by the 20 action of the plunger 99 and movement of the parts of said holder. The shank 98 of the plunger 99 can be made of any suitable shape, but by preference is rectangular in cross section as shown and has on its upper portion a transversely extended pin or stop 25 117 to restrict the upward movement of a weighted sleeve 118 which is loosely mounted on the shank 98 and rests on the arm 96 near its rear end to give better gripping effect to 30 said arm. By reference to Fig. 10 it will be noticed that the openings 95 and 97 in the arm 96 are somewhat larger than the pin 94 and shank 98 respectively so that said arm will be inclined by reason of its weight 35 as well as of the weight of the sleeve 118 which rests thereon. When thus inclined it is obvious that the walls of the opening 97 in the arm 96 will grip the shank 98, thus holding said shank and the plunger 99 stationary 40 until the arm 96 strikes the horizontal portion 90 of the arm 89, when it is apparent that the arm 96 will be slightly raised at its rear end, thus releasing the shank 98 and allowing it and the plunger 99 to descend 45 with considerable force onto the labels 116 within the holder.

Mounted on the upper portion of the rod 49 and extending rearwardly therefrom and slightly toward the wheel 34 is an arm 119 50 which has vertically and loosely mounted

thereon, near its free end, a rod 120 which carries on its lower end a brush body 121 which is provided with depending bristles 122 to form a brush to be used for tamping the labels after they have been attached to 55 the packages through the instrumentality of the label holder and its weighted plunger. The rod 120 is provided below the arm 119 which supports it, with an annular shoulder 123 between which shoulder and arm 119 is 60 interposed a coiled spring 124 which will afford resiliency to the brush. The upper end of the rod 120 is screw-threaded and has engaging with the said screw-threaded portion a nut 125 which can be used for regulating the tension of the spring 124 by turning said nut in the proper direction.

The operation of the machine is simple and as follows: Assuming that the parts are 65 in the positions shown in Fig. 1, of the drawings, and that the glue pot 73 is supplied with glue or paste, and the label holder 102 is loaded with labels, it is manifest that the packages can be placed in the hopper 29 one upon another, when by applying power 70 to the driving shaft 33 through the medium of the wheel 34, either manually or otherwise, and causing said shaft to turn in the proper direction, the feeding plunger 27 and its carrier 24 will be caused to advance, thus 75 forcing the lower package forwardly through the opening 32 in the lower portion of the hopper and between the springs 20 and bar 19, in which operation the cams 61 on the shaft 33 will be turned so as to diminish the pressure on the rollers 50 carried by the rods 46 to 49 inclusive, at the proper times, to permit said rods to be raised by the action of the springs 51 and 59 which 80 actuate them. As soon as one of the packages 21 has been ejected from the lower portion of the hopper 29, the feed plunger 27 and its carrier 24 will be retracted by the tension of the spring 59 acting on the rod 47 and through its connections with said 85 carrier. In the above mentioned movement of the rods 46—48 and 49 it is apparent that as the glue-pot, label-holder and tamping-brush are respectively connected to said rods they will be carried thereby, but that the 90 glue-pot as well as the label-holder will have independent movement from their respective rods, as well as, independent movement from their respective plungers, when the first or lowermost packages shall have been pushed from the hopper, the glue-pot will descend and strike with its perforated bottom the 95 upper surface of said packages and thus allow glue or paste to be supplied thereto through said perforations, the quantity being regulated to some extent, by the action of the plunger 77 which will also act as an agitator by reason of its independent movement. Now, as said package is advanced in the guideway by the succeeding package or 100

packages, it will pass under the label carrying holder 102 which descends in unison with the glue pot, and will have the lowermost label 116 therein applied and affixed to the adhesively coated surface of the packages by reason of the action on the labels of the weighted plunger 99, which in the descent of the holder 102, as well as of itself and shank 98, will be released from the gripping arm 96 by the latter striking the horizontal part 90 of the arm 89 which depends from the housing 16 and is extended across the path of the said gripping-arm. As the thus labeled package is advanced from the label-holder it will pass under the brush body 121 and be pressed by the bristles 122 thereof, which body will be reciprocated substantially in unison with the glue-pot and label holder. In the further operation of the machine, the above named steps will be repeated for each package, and it is apparent that each package as it passes under the glue-pot will have distributed over its upper portion paste or glue, and as it passes under the label holder a label will be affixed thereto through the instrumentality of the plunger 99, and as said packages pass under the brush they will be tamped thereby, or gently tapped so as to remove wrinkles from the labels and cause them to be smoothly and securely affixed to the packages. As the brush body 121 is loosely mounted on the arm 119 and actuated by the spring 124 it is obvious it will have independent movement from the rod 49 which carries said brush.

Having thus fully described our invention, what we claim as new and desire to secure by Letters Patent is—

1. In a label affixing machine, the combination with a main frame including a base and an upright part mounted thereon, of a hopper mounted vertically above said base, a vertically reciprocal glue pot, a plunger located in said pot, a vertically reciprocal label holder, a label striking plunger located in said holder, means to simultaneously reciprocate the said pot and holder, means to vertically move said plungers independently, and means to automatically release the label striking plunger.
2. In a label affixing machine, the combination with a main frame including a base and an upright part mounted thereon, of a hopper mounted above the base, a vertically reciprocal glue pot, a plunger located in the same, a vertically reciprocal label holder, a label affixing plunger located in said holder, a vertically movable tamping-brush, means to simultaneously reciprocate the said pot, holder and brush, means to independently and vertically move said plungers, and means to automatically release the striking plunger.
3. In a label affixing machine, the combination with a main frame, of a hopper mounted thereon, a vertically reciprocal glue pot, a vertically reciprocal label holder, an apertured plunger located within said pot and adjustably mounted, a vertically movable and gravity actuated label striking plunger located within said holder, means to simultaneously reciprocate the said pot and holder, means to vertically move said plungers independently of their respective receptacles, and means to automatically release the label striking plunger.

4. In a label affixing machine, the combination with a main frame including a base, of a hopper mounted above the base and having an opening in its lower portion, a horizontally reciprocal feeding device longitudinally mounted on the base and adapted to be projected into said opening of the hopper, a vertically movable glue pot having means in its lower end to discharge an adhesive, an apertured plunger located in said pot and having independent vertical movement from the same, a vertically movable label holder, a label striking plunger having independent vertical movement from and carried within said holder, means to reciprocate the feeding device, means to raise and lower said pot and holder as well as the plungers carried therein.

5. In a label affixing machine, the combination with a main frame having a base, of a hopper mounted above the base and having an opening in its lower portion, a horizontally reciprocal feeding device longitudinally mounted on the frame and extended above said base and adapted to be projected into said opening of the hopper, a vertically movable glue pot having means in its lower end to discharge an adhesive, an apertured plunger located in said pot and having independent vertical movement from the same, means to adjust said plunger with respect to said pot, a vertically movable label holder, a label striking plunger having independent vertical movement from said holder and located within the latter, means to reciprocate the feeding device, means to raise and lower the glue pot and label holder as well as the plungers located therein, and means to raise said plungers independently of their respective receptacles, and means to automatically release the label striking plunger.

6. In a label affixing machine, the combination with a main frame having a base, of a hopper mounted above the base and having in its lower portion an opening for the passage of packages, a horizontally reciprocal feeding device longitudinally mounted on the frame and extended above said base and adapted to be projected into said opening of the hopper, a vertically movable glue pot having means in its lower portion for the discharge of an adhesive, a perforated and slotted plunger located in said pot and

adjustably mounted, a vertically movable label holder, a vertically movable and gravity actuated label striking plunger located within said holder, a vertically movable and resiliently supported tamping brush, means to reciprocate the feeding device, means to raise and lower the glue pot, the label holder, and tamping brush as well as said plungers, means to raise said plungers independently of their respective reciprocations, and means to automatically release the striking plunger.

7. In a label affixing machine, the combination with a main frame, of a driving shaft horizontally journaled on said frame, means to drive said shaft, a hopper mounted near said main frame and having an opening in its rear lower portion, a horizontally reciprocal feeding device mounted near said hopper, a shaft transversely journaled on the lower portion of the main frame, an arm extended from said shaft, a connection pivotally uniting said arm and said feeding device, another arm extended from said transverse shaft, a spring actuated rod pivotally connected at its lower end to the last named arm and extended vertically, a roller on the upper end of said rod, and a cam on the driving shaft in contact with said roller.
8. In a label affixing machine, the combination with a main frame, of a driving shaft horizontally journaled on said frame, means to drive said shaft, a hopper mounted near said frame and having an opening in its lower portion, a horizontally reciprocal feeding device mounted near said hopper, a shaft transversely journaled on the frame, an arm extended from said shaft, connections pivotally uniting said arm and feeding device, another arm extended from said shaft, a vertically movable spring-actuated rod pivotally connected at its lower portion to the last named arm, a roller on the upper portion of said rod, a cam on the driving shaft in contact with said roller, another spring-actuated rod vertically mounted on the frame, a roller on its upper portion, a cam on the driving shaft in contact with said roller, a glue pot carried by the last named rod but having independent movement therefrom, a perforated plunger located within said pot and adjustably mounted on said rod.
9. In a label affixing machine, the combination with a main frame, of a driving shaft horizontally journaled on said frame, means

to drive said shaft, a vertically movable spring actuated rod mounted on the main frame, a roller on the upper portion of said rod, a cam on the driving shaft in contact with said roller, a label holder carried by said rod but having independent movement therefrom, an arm loosely mounted at one of its ends at the upper portion of said rod and having in its other end a vertical opening, and a weighted plunger located in the label holder and having a shank extended upwardly therefrom through the last named opening in said arm.

10. In a label affixing machine, the combination with a main frame, of a driving shaft horizontally journaled on said frame, means to drive said shaft, a vertically movable spring-actuated rod mounted on the main frame, means on the driving shaft and on the upper portion of said rod to depress the latter when said shaft is turned, a vertically disposed bracket carried by the upper portion of said rod and having a horizontal extension at each of its ends, an upright pin on the upper extension, a label holder having at its upper portion an extension to engage the lower extension of said bracket, an arm loosely mounted at one of its ends on said pin and having in its free portion a vertical opening, and a weighted plunger located within the label holder and having a shank extended upwardly therefrom through the last named opening in said arm.

11. In a label affixing machine, the combination with a main frame, having a base, of a hopper mounted above the base, a vertically movable label holder, the label striking plunger located within said holder and having a shank extended upwardly therefrom, means to raise the holder, a gripping device for said shank consisting of an arm mounted at one of its ends for vertical movement and its other end having in its free portion a vertical opening, means operably connected to said arm for causing it to grip the shank and move it and the plunger away from the labels, and means to automatically release said arm from the shank to permit movement of the plunger in the downward direction.
